UNITED STATES PATENT OFFICE

155,414

DESIGN FOR A COMBINATION LIPSTICK CASING AND MIRROR

Murray Goldenstein, New York, N. Y.

Application August 3, 1948, Serial No. 147,902

Term of patent 3½ years

(Cl. D86—10)

To all whom it may concern:

Be it known that I, Murray Goldenstein, a citizen of the United States, residing at 156 East 97th Street, New York city, in the county of New York and State of New York, have invented a new, original, and ornamental Design for a Combination Lipstick Casing and Mirror, of which the following is a specification, reference being had to the accompanying drawing, forming part thereof.

In the drawing

Fig. 1 is a front elevational view of a combination lipstick casing and mirror, showing my new design; the opposite side being identical;

Fig. 2 is a side elevational view thereof; and
Fig. 3 is a top plan view.

I claim:

The ornamental design for a combination lipstick casing and mirror, substantially as shown.
